UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed December 15, 1924. Serial No. 755,905.

This invention relates to sound-proof cabinets for typewriting machines, and more particularly to means to partially open the normally closed cabinet to give access to 5 finger-pieces on the carriage.

Sound-proof cabinets have been provided for typewriting machines in which the finger-pieces on the carriage of the typewriter machine extend through a slot in 10 the cabinet to the exterior thereof, so that the carriage may be operated from the outside. In cabinets of this kind it is not only necessary to replace the usual finger-pieces on the carriage by especially long ones, but 15 it is also necessary to provide the cabinets with suitable slot-sealing devices to prevent leakage of sound from the cabinets and between which said finger-pieces extend.

An object of the present invention is to 20 so construct a sound-proof cabinet that it may be produced at a minimum of cost. To this end, the necessity of special finger-pieces on the typewriter carriage has been avoided. The usual finger-pieces are used, 25 and provision is made whereby the cabinet may be partially opened so that the hand of the operative may pass through said opening to said finger-pieces to manipulate the carriage.

30 The cabinet of this invention is composed of a body-part to fit around the frame of the machine and a cover on said body-part. Said cover extends over the carriage of the machine and is pivoted on the body-part in 35 such a manner that it may be swung in the direction in which the hand is moving when reaching for the desired finger-piece on the carriage.

A finger-piece in the form of a flange is 40 provided at the upper end of the cover with which the hand may first engage to open the cabinet, after which the same hand may slip down from said finger-piece through the opening to the desired finger-piece on the 45 carriage. A hand or finger-rest is provided on the body of the cabinet along which the finger may slide while the carriage is being returned to the beginning of a writing line. The finger-piece on the cover is elongated 50 and extends the full length of the cover, so that it may be engaged at any point lengthwise thereof according to the position of the finger-pieces on the carriage. To facili-

tate opening the cabinet, there is connected to the cover a spring which normally tends 55 to open said cover but is overcome by the weight of the cover, the center of gravity of which is to one side of its pivot. Said spring is also effective to hold the cover open when it is swung all the way back.

Instead of opening the cover with the same hand which is to engage the finger-piece, as above explained, it may be desirable at times to open the cover with one hand while the other reaches through the opening 60 to the finger-piece on the carriage. To this end there is provided a key which may be supported on the body of the cabinet, said key when actuated being effective to push the cover back to open the cabinet. It will 65 be understood that the cover may be sprung back a considerable extent for the purpose of giving access to the platen, as, for instance, when inserting a new work-sheet into the machine. The key for swinging said cover, however, is effective to swing said cover only a short distance sufficiently to permit passage of the hand into the cabinet. To permit the cover to be swung through a predetermined distance by the key, there is 70 provided a stop to limit the motion of said key.

The cabinet is composed of three parts, 75 namely, a pack or shoe to fit around the frame of the machine, a cover pivotally supported on said shoe, and extending over the carriage, and a front plate against which the cover rests. Both the shoe and the front plate are secured to the typewriter frame. The cover is pivoted on the shoe and is inclined upwardly and forwardly and abuts 80 against inclined flanges at the sides of the front plate.

Other features and advantages will hereinafter appear.

In the accompanying drawings, 95 Figure 1 is a side view of the casing in elevation, showing the cover partly open for operating the carriage-control levers.

Figure 2 is a cross-sectional view in elevation through the line 2—2 of Figure 4, showing the cover closed and the typewriting machine enclosed therein.

Figure 3 is a fractional view in cross-section through the line 3—3 of Figure 4, 100 and shows one of the devices for partially

opening the cover to operate the carriage-control levers.

Figure 4 is a front view of the casing in elevation, and shows the different sections 5 composing the same.

The Underwood standard typewriting machine comprises a main frame 10, and has a forward extension 11 carrying banks of keys 12, operating type-bars 13 to cause 10 types 14 to strike against a platen 15 journaled in platen-frames which form part of a carriage 16. Said carriage is mounted for letter-feed movement upon rails which form an integral part of the main frame, and is 15 provided with controlling levers 17 for operating the carriage and the platen.

It is for the deadening of the sounds arising from the operation of a typewriting machine of this general character that this 20 sound-deadening casing is provided.

Referring more particularly to Figure 2, it will be seen that the casing is normally closed and that a cover 18 is held in a closed position by its own weight and against a 25 spring 19, which tends to open the same but is not strong enough to overcome the weight of the cover 18. The function of said spring is to counterbalance the weight of the cover, so that the same may be rocked on fulcrum-screws 20 and swung backwardly to partially 30 open the same, as shown in full lines in Figure 1, with a minimum effort on the part of the operative.

In order to operate the carriage-control 35 levers normally enclosed in the casing, it is necessary to partially open the cover 18 so that the hand may reach through the opening to the levers, as indicated in Figure 1, in which a finger 21 is shown in the slot formed 40 between the cover 18 and a front closure 22. The cover may be either pushed backwardly by the end of the fingers striking a rib 23 along the front edge, or it may be operated by means of one of two buttons 24 at both 45 extreme ends of the front closure 22. Said button 24 is fast to a plunger pin 25 around which a spring 26 is wound to restore the same to normal position, as shown in Figure 3. The spring 26, as shown in the drawings, 50 is a compression spring and actuates between the button 24 and a narrowed portion 27 in a hole which serves as a bearing for the plunger 25. Said plunger 25 is provided with a rounded end 28 for engaging the edge 55 29 of the cover 18.

The casing comprises three main parts or sections, a lower member 30 upon which there is rockably mounted the cover 18, and the front closure 22.

60 The lower box-like member 30 is designed to snugly fit over the typewriter framework, to which it is fastened by means of the regular typewriter feet 31, which serve as means for holding the lower member and the frame 65 of the typewriter together. The member 30

is provided with a lining 54 of some sound-deadening material, and the feet 31 are screwed into the typewriter frame through holes in the member 30 in positions corresponding to the tapped holes in the frame. 70

The front closure 22 is fastened to the typewriter frame by means of screws 32 in place of the usual front plate found in the Underwood machine. Said front closure extends the full width of the cover 18, and at 75 the ends there are provided rearwardly-extending portions 33 which snugly fit the outline of the lower member 30 at 34. The borders of the front closure are provided with a soft strip 35 designed to effectively close 80 the opening formed between said front closure and the cover 18. There is also provided a felt covering 36 fast to the inner side of the front closure. At the ends of the front closure 22 there are provided bosses 85 37 for receiving the plungers 25, the object of which has been hereinbefore described.

In order that a work-sheet 38 may be inserted around the platen 15, the cover is 90 designed to be swung farther back to a position shown in dot-and-dash lines in Figure 1. For this purpose there is provided a stop device which comprises a pin 39 and a bent portion 40 which forms an integral part of the cover 18. It will be noted that the spring 19 assists in keeping the cover in this position against the stop pin 39. Another feature of the cover is a pocket 41 at the rear for receiving the overhanging portion of 95 the work-sheet, said pocket being formed by the rear wall 42 of the lower member 30, the rear wall 43 of the cover 18, and a lower connecting wall 44 which forms an integral part of said cover and extends forwardly to meet the wall 42 at 45. In order to lower 100 the fulcrum point upon which the cover is swung, there are provided two downwardly-extending ears 46, which serve as bearings for the fulcrum screws 20. The wall 44 is forwardly extended to form pockets at the 105 ends in which the carriage enters when letter-spaced to a position beyond the frame of the machine, and is provided with an upwardly and forwardly extending portion 47 in line with an extension 48, which forms an 110 integral part of the front closure 22. 115

The printing point is rendered visible by the provision of a window in the cover 18, having a glass 49 fastened to the cover 18 by means of a plate 50 and screws 51. It will be noted that at the front the glass 49 is held in a groove 52, while at the sides (not shown) and at the rear provision is only made for holding the glass against outward pressure, so that the glass may be inserted 120 in the groove 52 and forced into place and held there by means of the plate 50. 125

In order to further deaden the noise arising from the operation of the machine, the cover is provided with a lining 53 of some 130

sound-deadening material, such as felt. Said lining is also extended to cover the pockets for the carriage at the ends of the cover.

It will be seen that the casing is of such construction that when the typewriter is operatively installed therein there is no opening through which the sound arising from the operation of the machine may escape. This invention therefore provides a sound-deadening casing which, although not so efficient in regard to operation of the carriage-levers as those casings provided with slot-sealing cushions through which the carriage-controlling levers protrude, is more efficient in its noise-eliminating properties, and has the added advantage that the typewriter may be placed in the casing with little or no alteration thereof.

It will also be seen that, due to the general design of the different sections composing this casing, the same adapts itself to be interchangeably manufactured within liberal limits, and therefore can be produced at a comparatively low cost.

25 Variations may be resorted to within the scope of the invention, and portions of the improvements may be used without others.

Having thus described my invention, I claim:

30 1. The combination with a typewriting machine having a carriage and finger-pieces on said carriage, of a closed sound-proof cabinet to enclose the machine, including said finger-pieces, said cabinet comprising a closing element pivoted to swing mainly rearwardly in the vicinity of said finger-pieces, and movable rearwardly out of the way by movement of the hand of the operative rearwardly toward any one of the finger-pieces on the carriage, to partially open said cabinet to form a front hand-opening to give access to the finger-pieces on the carriage.

2. The combination with a typewriting machine having a carriage and finger-pieces on said carriage, of a closed sound-proof cabinet to enclose the machine, including said finger-pieces said cabinet comprising a closing element pivoted to swing mainly rearwardly in the vicinity of said finger-pieces, and movable rearwardly out of the way by movement of the hand of the operative rearwardly toward any one of the finger-pieces on the carriage, to partially open said cabinet to form a front hand-opening to give access to the finger-pieces on the carriage, and a finger-piece extending along said pivoted element and engageable anywhere throughout the length of the pivoted element, for opening the same.

3. The combination with a typewriting machine having a carriage and finger-pieces on said carriage, of a closed sound-proof cabinet to enclose the machine, including said finger-pieces, said cabinet comprising a

closing element pivoted to swing mainly rearwardly in the vicinity of said finger-pieces, and movable rearwardly out of the way by movement of the hand of the operative rearwardly toward any one of the finger-pieces on the carriage, to partially open said cabinet to form a front hand-opening to give access to the finger-pieces on the carriage, a finger-piece extending along said pivoted element and engageable anywhere throughout the length of the pivoted element, for opening the same, and a finger-rest on said cabinet adjacent the opening.

4. The combination with a typewriting machine having a carriage and manipulable devices on said carriage, of a closed sound-proof cabinet to enclose the machine and manipulable devices and render the latter inaccessible, said cabinet comprising a body-part, a cover on said body-part, a finger-piece connected to said cover to swing it to partially open said cabinet to give access to the manipulable devices on the carriage, and means for limiting the extent of opening of said cabinet effected by said finger-piece, to form no more than a hand-opening.

5. The combination with a typewriting machine having a carriage and manipulable devices on said carriage, of a sound-proof cabinet to enclose the machine and said devices, said cabinet comprising a body-part, a cover on said body-part, a finger-piece connected to a plunger to swing said cover to partially open said cabinet to give access only to the manipulable devices on the carriage, and a stop to engage said plunger to determine the extent of opening of said cabinet effected by said cover-swinging finger-piece.

6. The combination with a typewriting machine having a carriage and finger-pieces on said carriage, of a closed sound-proof cabinet to enclose the machine and the finger-pieces, in their entirety, said cabinet comprising a pack fitted around the frame of the machine, a front plate carried by the machine and a cover pivoted on said pack, and a finger-piece on said front plate to swing said cover to partially open said cabinet to form a hand-opening to give access to the finger-pieces on said carriage.

7. The combination with a typewriting machine, of a sound-proof casing for said machine, said casing comprising a body-part to fit around the frame of said machine and a cover pivoted on said body-part, and a detachable front plate, said front plate having rearward extensions to form with said cover carriage-chambers extending beyond the sides of said body-part, the bottom of said cover being inclined upwardly and forwardly, said front plate having inclined flanges at its sides with which the inclined portion of the cover engages.

8. The combination with a typewriting machine having a carriage, of a sound-deadening cabinet for said machine, said cabinet comprising a pack fitted around and directly upon the frame of the machine, means to clamp said pack to said frame to subdue noise vibrations, a cover pivoted on said pack, said cover substantially longer than said pack, to form a chamber in which the carriage may travel, and having ends overhanging said pack, a front plate secured to the frame of the machine, said front plate serving as a front closing abutment for said cover, and means partly on said front plate 10 and partly on said cover, for closing the bottom of the overhanging ends.

9. The combination with a typewriting machine, of a sound-deadening cabinet for said machine, said cabinet comprising a pack 20 fitted around the frame of the machine, means to secure said pack to said frame, a cover pivoted on said pack, said cover being inclined upwardly and forwardly at the bottom, and a front plate secured to the frame 25 of the machine, said front plate having inclined flanges to serve as a closing abutment for said cover.

10. The combination with a typewriting machine including a carriage having finger-pieces, of a sound-proof cabinet to completely enclose said machine except the keyboard extension, said cabinet comprising a pack 30 fitted closely around said frame and absorbing vibrations therefrom, a cover pivoted on said pack, a detachable front plate, said cover and front plate co-operating to form a carriage chamber of substantially greater length than the pack and overhanging the same, and means to partially open said cover 35 to form a hand-hole to give access to the finger-pieces on the carriage of the machine at all positions of said carriage.

11. The combination with a typewriting machine having a carriage and controlling levers therefor, and including a frame and tapped holes for receiving supporting feet, of a casing, comprising three sections, namely, a lower member around the frame and fastened thereto by means of said feet, a 45 hood pivoted on said lower member and a front closure fastened to the frame of the machine, for effectively enclosing the opening formed between the lower member and the hood, the three sections completely enclosing the typewriter except for the keyboard section which protrudes through an opening at the front.

12. The combination with a typewriting machine having a carriage and controlling levers therefor, and including a frame and tapped holes for receiving supporting feet, of a casing, comprising three sections, namely, a lower member around the frame and fastened thereto by means of said feet, a 60 hood pivoted on said lower member and a front closure fastened to the frame of the machine, for effectively enclosing the opening formed between the lower member and a

front closure fastened to the frame of the machine, for effectively enclosing the opening formed between the lower member and the hood, the three sections completely enclosing the typewriter except for the keyboard section which protrudes through an opening at the front, and means whereby the hood may be partially opened by swinging the same to the rear to give access to the controlling levers on the carriage. 70

13. The combination with a typewriting machine having a carriage and controlling levers therefor, and including a frame and tapped holes for receiving supporting feet, of a casing, comprising three sections, namely, a lower member around the frame and fastened thereto by means of said feet, a hood pivoted on said lower member and a front closure fastened to the frame of the machine, for effectively enclosing the opening formed between the lower member and the hood, the three sections completely enclosing the typewriter except for the keyboard section which protrudes through an opening at the front, and means whereby the hood may be partially opened by swinging the same to the rear to give access to the controlling levers on the carriage, 75

80 said means comprising a plunger operatively mounted in said front closure and held in its effective position by means of a spring, a button for operating said plunger and a rib forming an integral part of said hood and operatively engaging said plunger. 90

14. The combination with a typewriting machine having a carriage and controlling levers therefor, and including a frame and tapped holes for receiving supporting feet, of a casing, comprising three sections, namely, a lower member around the frame and fastened thereto by means of said feet, a hood pivoted on said lower member and a front closure fastened to the frame of the machine, for effectively enclosing the opening formed between the lower member and the hood, the three sections completely enclosing the typewriter except for the keyboard section which protrudes through an opening at the front, means whereby the hood may be partially opened to give access 100 to the controlling levers of the carriage, and means whereby the hood may be fully opened to give access to a work-sheet to manipulate the same. 110

15. The combination with a typewriting machine having a carriage and controlling levers therefor, and including a frame and tapped holes for receiving supporting feet, of a casing, comprising three sections, namely, a lower member around the frame and fastened thereto by means of said feet, a hood pivoted on said lower member and a front closure fastened to the frame of the machine, for effectively enclosing the opening 120 formed between the lower member and a

the hood, the three sections completely enclosing the typewriter except for the keyboard section which protrudes through an opening at the front, means whereby the 5 hood may be partially opened to give access to the controlling levers of the carriage, and means whereby the hood may be fully opened

to give access to a work-sheet to manipulate the same, said last-mentioned means comprising a stop-device for determining the 10 amount that the hood may be opened and a spring to assist the swing of the hood while being opened.

JOHN WALDHEIM.
